(57) **CLAIM**

The ornamental design for a cover assembly for a patient transport apparatus, as shown and described.

DESCRIPTION

FIG. 1 is a front, top, left side, perspective view of a first embodiment of a cover assembly for a patient transport apparatus;

FIG. 2 is a rear, top, left side perspective view of the cover assembly for a patient transport apparatus of FIG. 1;

FIG. 3 is a rear, bottom, left side perspective view of the cover assembly for a patient transport apparatus of FIG. 1;

FIG. 4 is a front view of the cover assembly for a patient transport apparatus of FIG. 1;

FIG. 5 is a rear view of the cover assembly for a patient transport apparatus of FIG. 1;

FIG. 6 is a left side view of the cover assembly for a patient transport apparatus of FIG. 1;

FIG. 7 is a right side view of the cover assembly for a patient transport apparatus of FIG. 1;

FIG. 8 is a top view of the cover assembly for a patient transport apparatus of FIG. 1;

FIG. 9 is a bottom view of the cover assembly for a patient transport apparatus of FIG. 1;

FIG. 10 is a front, top, left side, perspective view of a second embodiment of a cover assembly for a patient transport apparatus;

FIG. 11 is a rear, top, left side perspective view of the cover assembly for a patient transport apparatus of FIG. 10;

FIG. 12 is a rear, bottom, left side perspective view of the cover assembly for a patient transport apparatus of FIG. 10;

FIG. 13 is a front view of the cover assembly for a patient transport apparatus of FIG. 10;

FIG. 14 is a rear view of the cover assembly for a patient transport apparatus of FIG. 10;

FIG. 15 is a left side view of the cover assembly for a patient transport apparatus of FIG. 10;

FIG. 16 is a right side view of the cover assembly for a patient transport apparatus of FIG. 10;

FIG. 17 is a top view of the cover assembly for a patient transport apparatus of FIG. 10; and,

FIG. 18 is a bottom view of the cover assembly for a patient transport apparatus of FIG. 10.

In the drawings, the broken lines represent unclaimed portions of the cover assembly for a patient transport apparatus and form no part of the claimed design.
